CURTAIN STRETCHER

Walter W. Block, Kenosha, Wis., assignor to
Quaker-Stretcher Company, Kenosha, Wis., a
corporation of Wisconsin

Application August 31, 1944, Serial No. 552,031

7 Claims. (Cl. 45—24)

1

This invention relates generally to curtain stretchers, and more particularly to improved means for securing curtain stretcher pins within wooden frame members.

It has been common practice for many years to provide curtain stretchers comprised of wooden frame members having a plurality of pins arranged in spaced relation along one margin thereof. One portion of the pin is embedded within the frame and the other portion projects from the frame a sufficient distance to accommodate fabric materials. In my Patent No. 2,232,047 I have shown a curtain stretcher frame equipped with pins for holding woven material. As illustrated in this patent, the pin is preferably driven into the wooden structure of the frame. Experience has shown that pins thus carried by wooden stretcher frames have a tendency to loosen as a result of climatic changes to which the wooden frame structure is subjected. If the pins are driven into the frame when the wood is not completely dry, further drying of the wood causes shrinkage of the wood fibers adjacent the pin and consequent tendencies for the pin to loosen. Also, some wood materials grip pins better than others, and hence it has been difficult to maintain uniformity in the firmness with which pins are secured in place. When the frames are made of relatively soft wood the pins oftentimes are not held in place with sufficient firmness. It is an object of the present invention to overcome the aforesaid difficulties by providing a curtain stretcher frame and pin structure in which the pins are positively secured against loosening by new and novel means.

More specifically, the invention contemplates a combined frame and pin structure of the type just referred to wherein a portion of the frame is composed of material which will impinge the pins more aggressively than the fibers of conventional solid wooden frames.

The invention contemplates a curtain stretcher device in which the frame thereof carries as a unit an insert or strip of material which is less subject to contraction or expansion than the wooden structure of the frame, and hence capable of securing against loosening a pin driven therethrough.

A further object is to provide in association with the wooden frame of a curtain stretcher a section of material which is considerably more impervious to moisture than the wooden frame, and hence capable of more firmly securing pins within the frame.

The foregoing and other objects and advan-

tages will be more apparent from the following detailed description when considered in connection with the accompanying drawing wherein:

Figure 1 illustrates in perspective a curtain stretcher capable of employing the present invention;

Figure 2 is an enlarged fragmentary transverse sectional view of one of the wooden frame members taken substantially along the line 2—2 of Figure 1 to more clearly illustrate the manner in which the curtain stretcher pin is positively secured within the frame;

Figure 3 is a view similar to Figure 2 illustrating the frame and insert structure of Figure 2, having in association therewith a modified pin which is driven into the frame from the rear side thereof, as distinguished from the pin in Figure 2, which is driven into the frame from the front side thereof; and

Figure 4 is a perspective view disclosing fragmentary portions of the frame and insert in disassociated relation.

Referring now to the drawing, wherein like numerals have been employed to designate similar parts throughout the various views, it will be seen that one embodiment of the invention is incorporated in a curtain stretcher designated generally by the numeral 10, Figure 1.

In the disclosed embodiment the curtain stretcher is made up of a plurality of upright frame members 12, 14, 16 and 18, as well as upper and lower frame members or sections 20 and 22, respectively. The present invention does not concern the relative disposition of the frame members but is directed primarily to the manner in which curtain stretcher pins 24 are retained within the frame members.

Figure 2 constitutes a sectional view taken substantially along the line 2—2 of the frame member 16. It will be noted that the section is taken medially of one of the pins 24 so as to more clearly illustrate the manner in which said pin is secured within the wooden frame member. As previously pointed out, experience has shown that pins mounted within solid wooden frames have a tendency to become loose. In some instances this results from the tendency of the wood fibers to shrink away from the pin as the wood dries. Thus, if the pin is driven into the wooden frame before the wood has completely dried there is ever present the danger of the pin subsequently becoming loose. Also, relatively soft, loose fibered wood frequently does not firmly impinge the pin periphery. To overcome these difficulties the present invention contemplates a

wooden frame member, such as the wooden frame member 16 of Figure 2, having associated as a unit therewith a member or strip 26 which is more stable than soft wood under varying atmospheric conditions and presents a firm or aggressive surface grip to a pin. It has been found, for example, that if the member or insert 26 is made of plastic or certain fibrous laminated materials which will not crack when the pin is driven therethrough, said pin may be permanently secured against loosening.

One embodiment of the invention contemplates a wooden frame, such as the frame member 16, formed with an elongated slot or opening 28, Figure 4, designed to receive the plastic or moisture impervious member 26. The insert 26 may be pressed into the slot 28 or otherwise secured therein. After the insert has been secured as a unit of the frame member the pin 24 may be driven into position, as shown in Figure 2. This type of pin is driven in from the front side of the frame a sufficient distance to penetrate the insert 26. The frame member 16 is cut away at 28 so as to present a narrow section 16a and a heavier section 16b. The portion of the pin 24 projecting beyond the front surface of the narrow section 16a serves to accommodate woven materials such as curtains, fabrics, and the like.

In Figure 3 the frame 16 and the insert 26 are identical with the frame structure shown in Figure 2. A modified pin 30 is shown in Figure 3, said pin being driven through the narrow section 16a of the frame from the rear side of the frame. The pin 30 is provided with a head at its lower extremity which limits the extent to which it may be driven into the frame. Both of the pins 24 and 30 are preferably driven completely through the moisture impervious member or insert 26 and are equipped with knurled or barbed surfaces to facilitate gripping within the frame structure.

From the foregoing it will be apparent that by employing the auxiliary frame insert 26, any variations in the wooden frame part, such as the shrinkage of the wood fibers from the peripheral surface of the pins, or the normal looseness of natural wood fibers, will not cause said pins to loosen. That is to say, the material of the insert 26 is relatively stable compared with the wood fibers of the frame proper and hence said insert firmly and uniformly impinges the peripheral surface of the pins at all times. Certain types of laminated plastic materials have proven successful, but obviously the invention is not limited to any specific insert material. However, the composition of the material must be such as to maintain a snug or tight fit of the pins within the insert during the life of the curtain stretcher of which the frame forms a part. Stating it another way, the pin accommodating section or insert should have a co-efficient of expansion due to atmospheric moisture which is substantially less than the wooden frame member whereby permanently to secure the pins within the frame member. It is also preferable that the insert be substantially free from shrinkage in a substantially dry atmosphere as compared with the natural wood fibers of the frame.

For purposes of illustration one form of auxiliary frame member, such as the insert 26, has been shown. Obviously, various forms and shapes of pin receiving members may be combined as a unit with the main frame structure without departing from the spirit and scope of the appended claims.

The invention is hereby claimed as follows:

1. In a frame structure for curtain stretchers and the like, an elongated frame member having a longitudinal groove therein, an insert carried by said frame member and substantially filling said groove and formed of a material capable of more firmly, constantly, and uniformly gripping pins to be inserted therein than wood and less affected by temperature and humidity changes, and a plurality of pins each having the outer end thereof disposed exteriorly of said frame member a distance sufficient to accommodate woven materials and each having adjacent portions of the inner end thereof embedded in said frame member and said insert with substantial surface contact therewith whereby the insert will obviate any tendency of the pins to loosen.

2. In a frame structure for curtain and other fabric stretchers, an elongated frame member having a longitudinal groove disposed between the front and rear faces of the fabric gripping area thereof, an insert carried by said frame member and substantially filling said groove, and a plurality of pins having one extremity disposed exteriorly of the front face of said frame member a distance sufficient to accommodate the fabric and having the other extremity extending through the adjacent portion of said frame member and into substantial surface contact with said insert, said insert being more resistant to changes in conditions affecting gripping action on the pins than the frame member whereby to restrain said pins from loosening.

3. In a frame structure for curtain stretchers and the like, an elongated frame member having a longitudinal groove therein disposed between the front and rear faces and opening inwardly thereof, an insert carried by said frame member and substantially filling said groove and formed of a material capable of more firmly, constantly and uniformly gripping impaling pins to be inserted therein as compared to the frame member, and a plurality of pins each having the outer end thereof disposed exteriorly of said frame member a distance sufficient to accommodate woven materials and each having adjacent portions of the inner end thereof extending through said insert in continuous surface contact therewith, and embedded in said frame member on opposite sides of the insert whereby to restrain the pin from loosening.

4. In a frame structure for curtain stretchers and the like, an elongated frame member for transversely accommodating impaling pins, a plurality of impaling pins carried by said frame member with the outer ends of said pins protruding therefrom a distance sufficient to accommodate woven materials, and an insert substantially oblong in cross section carried by said frame member and in which inner portions of the pins are secured, the longer sides of the cross section of said insert contacting said frame member and a shorter side exposed, said insert consisting of a material permitting the pins to be driven therein through an imperforate portion thereof but effective to impinge the embedded pin surfaces more constantly and aggressively than wood whereby to permanently secure the pins thereto.

5. In a frame structure for curtain stretchers and the like, an elongated frame member for transversely accommodating impaling pins, a plurality of impaling pins carried by said frame member with the outer ends of said pins protruding therefrom a distance sufficient to ac-

commodate woven materials, and an insert substantially oblong in cross section carried by said frame member and in which inner portions of the pins are secured, the longer sides of the cross section of said insert contacting said frame member and a shorter side exposed, said pins having the inner end portions thereof roughened and said insert consisting of a material permitting the roughened ends of the pins to be driven therein through an imperforate portion thereof but effective to snugly impinge the embedded roughened ends of the pins for constantly and aggressively gripping the pins more firmly than wood whereby to permanently secure the pins thereto.

6. A curtain stretcher comprising means providing a polygonal frame structure having a plurality of recesses around the periphery thereof, a plurality of pins passing into said recesses and embedded in an adjacent portion of said frame structure, and each of said pins having the free end thereof disposed exteriorly of said frame structure a distance sufficient to accommodate the material to be stretched thereon, and an insert substantially filling each of said recesses and within which said pins are intimately gripped throughout the portions which extend therein, said insert consisting of a material which permits the pins to be driven thereinto but which is effective to grip the pins more firmly, constantly and uniformly than the material of the frame structure whereby to restrain the pins from loosening.

7. A curtain stretcher comprising means providing a polygonal frame structure having a plurality of recesses around the periphery thereof, an insert disposed within each of said recesses and formed of a material capable of gripping impaling pins to be inserted therein more firmly, constantly and uniformly than the material of the frame structure, and a plurality of impaling pins disposed around the periphery of said frame structure with the inner ends thereof extending transversely through said inserts and embedded in portions of said frame structure on opposite sides of said inserts and with the outer ends of said pins disposed exteriorly of said frame structure a distance sufficient to accommodate woven materials.
